UNITED STATES PATENT OFFICE.

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS.

FOLDER FOR SEWING-MACHINES.

1,135,708.

Specification of Letters Patent. Patented Apr. 13, 1915.

Application filed December 22, 1906. Serial No. 349,061.

To all whom it may concern:

Be it known that I, JAMES R. MOFFATT, a citizen of the United States, residing at Chicago, in the county of Cook, State of Illinois, have invented certain new and useful Improvements in Folders for Sewing-Machines, of which the following is a description, reference being had to the accompanying drawing and to the letters and figures of reference marked thereon.

My invention relates to folders for fabrics, and while said folder may be useful for various purposes, the same is more especially adapted for folding a collaret, so that the same is properly delivered to the stitching mechanism of a sewing machine, whereby said folded collaret is attached to a body fabric.

The object of my invention is to provide a folder of the above-indicated character, with a tension member bearing upon the folded edge of the strip passing through my folder, whereby the delivery of this folded strip to the stitching mechanism is so controlled that the edge is laid smoothly upon the body fabric, and a curved neck produced.

A further object of my invention is to provide the folder with a supplemental member, which places a yielding tension upon the strip at its middle fold, and which is also adjustable, so that the size of the fold may be slightly adjusted.

These and other objects will in part be obvious and in part be more fully herein-after described.

My invention consists in the novel parts and arrangements hereinafter shown and described.

In the accompanying drawings, which illustrate one embodiment of my invention, Figure 1 is a top plan view of the bed plate of a sewing machine with my improved folder attached thereto, the presser bar and the overhanging arm being shown in section; Fig. 2 is an elevation of my improved folder, as seen from the rear when viewed in Fig. 1; Fig. 3 is a longitudinal sectional view through the folder; Fig. 4 is an end elevation of the delivery end of the folder; Fig. 5 is a perspective view of the auxiliary tension member located within the folder; Fig. 6 is a detail view, showing the manner of folding and turning the binding strip, so as to properly position the same for attachment to the body fabric; and Fig. 7 is

a detail view of one of my thread-guiding arms, and the means for supporting the same.

The bed plate 1 is of the usual construction, and has coöperating therewith a presser foot 2, carried by a presser bar 3, as shown in section in Fig. 1. The feeding member 4, the needles 5, 5, and the looper rod 6, are of the usual construction, and will not need further description.

A thread-carrying looper preferably cooperates with the needles 5, 5, beneath the work plate, forming a cross stitch, but it will be obvious that any other form of complementary stitch-forming mechanism may be used in connection with the said needles.

The bed plate 1 is slotted as at 7 to receive my improved folder, so that when said folder is attached to the bed plate, a portion thereof extends beneath the surface of the bed plate, which facilitates the positioning of the folded strip above and below the body fabric being fed over the surface of the bed plate.

The folder 8 is attached to the front portion of the bed plate, by means of a shank 9, which is slotted at 10, 10, receiving screws 11, 11, which pass into the bed plate and hold the folder in its adjusted positions.

In front of the folder 8, I have located an edge guide 12, for the body strip, and said edge guide is adjustably secured to the bed plate by means of the screws 13, 13, passing through slots 14, 14, in said edge guide.

My improved folder is formed preferably by two spaced members 15 and 16, which are symmetrically curved and are preferably joined at their outer edges, forming in reality one continuous piece. Said members 15 and 16 at the receiving end of the folder are but slightly curved, so that the strip to be folded when received by the folder, is substantially flat.

The member 16 at the receiving end of the folder is extended and forms a support for my strip-guiding fingers 17 and 18. The finger 18 is formed integral with an arm 19, which is pivoted to the member 16 at the point 20. Said arm 19 is provided with a slot 21, intermediate the pivotal connection and the guiding finger. The finger 17 is formed integral with an arm 22, also shown as pivotally connected to the pivot 20, and said arm 22 is provided with a slot 23. The slots 21 and 23 in the arms 19 and 22 engage

a screw 24, by means of which said arms are held in their adjusted positions.

When it is desired to adjust the fingers 17 and 18 the screw 24 is loosened, and the arms 19 and 22 swung about their pivot 20, until they are properly located relative to the folder when the screw 24 is set, holding the arms in the position to which they have been adjusted. The members 15 and 16 of my folder as they approach the delivery end are bent toward each other, so as to fold the fabric upon itself, and the outer edges of said members are bent back upon themselves gradually toward the delivery end, so that the folded strip leading from the folder is not only folded upon itself, but has its edges turned back upon the outer face of said strip. The folded strip as it leaves the folder, is drawn between the projecting ends of the folder, so that the strip is reversed, and the folded edges which were turned upon the outer face of the strip as they pass through the folder, are now turned underneath the strip and against the body fabric. The forward end of the folder is provided with fingers 25, 25' against which the folded edge of the strip passes, as it is led from the folder.

Adjacent the delivery end of the folder, I have cut away the member 16, so as to expose the outer folded edge of the strip passing through the folder. In order to put a slight tension upon the folded edge passing through the folder, I have provided my folder with a tension member 26, which is provided at its forward end with arms 27 and 28, resting in the openings 29 and 30, above referred to. Said tension member is rigidly carried by a bracket 31, mounted on the folder, and intermediate the bracket 31 and the free end of said tension member is a post 32 carrying a plate 33, which rests on said tension member 26. Said post 32 is threaded at its outer end and carries a thumb nut 34, by means of which the plate 33 may be moved against the member 26, and the tension of said member increased or decreased, as desired.

Within the folder and between the members 15 and 16 I have located my auxiliary guiding and folding member 35. Said member 35 is secured to the member 16 of the folder, by a thumb nut 36, which engages a screw carried by the member 35, and passing through a slot 37, near the receiving end of said folder. The member 16 is also slotted near the delivery end of the folder, and a screw 37', carried by the member 35 projects through said slot. Said screw 37' carries a thumb nut 38, having an enlarged tapered head 39.

Extending from a post 40, formed integral with the folder is an arm 41, which is rigidly secured to the post 40 by means of a screw 42. Said arm 41 has an opening within which the thumb nut 38 is located, and the

sides of said arm 41 bear against the enlarged head of the thumb nut 38, as clearly shown in Fig. 3 of the drawing. This arm 41 is formed of spring metal, so that the free end of the auxiliary member 35 is yieldingly supported. The position of the free end of said auxiliary member, relative to the edge folders, may be adjusted by turning the thumb nut 38 and the position of the free end may be adjusted relative to the guiding fingers 25, 25', by loosening the thumb nut 36.

From the above description, it will be apparent that I have provided a folder or binder head which consists of spaced U-shaped guiding walls for guiding the binding strip in a direction transverse to the line of feed of the material being bound, and that the delivery end of the walls of the binder head are formed obliquely with respect to the binder head, whereby the binding may be inverted. I have also provided an auxiliary guiding or folding member 35, which engages the material at the fold therein, and over which the folded material is inverted. This guiding member is adjustable longitudinally of the binder head, so that the part over which the strip of fabric is inverted, may be brought closer to the extreme delivery end of the binder, or moved farther from the same. By this adjustment of the guiding member, the binder head or folder is adjusted so as to accommodate different widths of binding strips for collars.

Prior to this invention, it has been common to adjust the binder to accommodate different widths of binding strips by the use of fingers located at the extreme delivery end of the binder, and engaging the edges of the binding strip. When the binder is adjusted in this manner, the entire binder head must be reset, in order to bring the edges of the binding strip into the stitching line. In other words, for every change in the width of the binding strip, the binder head must be reset. By my improved method of adjustment however, wherein the guiding member at the fold in the strip over which guiding member the strip is inverted, is adjusted for varying widths of binding strips, this re-setting of the binder head is entirely avoided.

In order to maintain the proper angle at the delivery end of the binder, I prefer to adjust the guiding member laterally as well as longitudinally. It will be obvious however, that the real adjustment of the binder to accommodate different widths, is due to the longitudinal adjustment of the guiding member.

It will be noted that the extension of the member 16, which carries the guide arms 17 and 18 has its opposite edges tapered toward the rear end, and as the strip to be folded passes from the supply to the folder, the

outer edges thereof are drawn across these tapered edges and uncurled.

It will be noted that the guide fingers 25 and 25' attached to the extreme delivery end 5 of the folder serve the purpose of guiding the folded edge, so as to properly position the said folded edge relative to the needles. Without these guiding fingers it would not be possible to direct the folded edge of the 10 fabric so that lines of stitching could be placed close to the edge of the collaret. By placing the edges of the folded collaret under tension, these edges are stretched, and the finished product curved, forming what 15 is known as the circular neck. It will also be noted that by loosening the screws 11, 11, that the entire folder may be adjusted relative to the stitching mechanism, so that the position of the lines of stitching relative to 20 the folded strip may be varied. It will also be noted that by loosening the screws 13, 13, the edge guide for the body fabric may be adjusted, and the position of said body fabric, relative to the folded strip, changed. 25 When the auxiliary folding member is adjusted to make a smaller collaret, the edge guide is also adjusted, so as to properly locate the body fabric relative to the folder.

30 In the operation of my binding attachment or folder, the binding strip or collaret with its raw edges is passed into the folder at the receiving end thereof, and as said strip passes through the folder, it is folded centrally of its width, so that said strip is delivered in two relatively flat parallel horizontal layers. As said strip passes through the folder, the raw edges of the strip are turned over upon the outer faces of the strip 35 by the curved flanges or walls of the spaced U-shaped guiding members, so that when the strip reaches the front end of the folder, the raw edges will be flat against the outer faces of the strip. As the strip leaves the 40 folder, it is turned inside out or reversed, and simultaneously guided or fed in a direction at an angle (as for instance a right angle), to its initial direction of feed, so that the folded edges of the strip are brought 45 in opposition to each other, and in position to be sewed upon the top and bottom of the work which is fed over the cloth plate, in the usual manner. The feeding mechanism of the machine draws the material, together 50 with the facing or binding strip, under the presser foot in the well known manner. When it is desired to vary the capacity of the folder for different widths of binding strips, the auxiliary folding or guiding member 35 is adjusted longitudinally of the binder, so as to bring the end thereof over which the binding strip is inverted, closer to or farther from the extreme delivery tips of the binder, and by this 55 adjustment, the capacity of the binder is

varied to accommodate the width of the binding strip. After the guiding member is adjusted longitudinally, it is also preferably adjusted laterally, so as to maintain the delivery end of the binder at an angle of 70 forty-five degrees to the line of feed, as by this adjustment, the binding strip may be more smoothly inverted and guided to the stitching mechanism.

It is obvious that various minor changes in 75 the details of construction may be made without departing from the spirit of my invention.

Having thus described my invention, what I claim as new and desire to secure by 80 Letters Patent, is:—

1. A sewing machine, comprising in combination stitch-forming mechanism, feeding mechanism and a folder including in combination, a main folding member and an auxiliary folding member coöperating therewith, said auxiliary folding member being adjustable at its delivery end both laterally and longitudinally of said main folder, and means for holding the same in its adjusted 90 positions, said folder being located substantially at right angles to the line of feed; substantially as described.

2. A sewing machine, comprising in combination stitch-forming mechanism, feeding 95 mechanism and a folder including in combination, a main folding member and an auxiliary folding member for engaging the binding strip at the fold therein and over which said binding strip is inverted, said auxiliary folding member being adjustable longitudinally of said main folder, and means for holding the same in its adjusted 100 positions, said folder being located substantially at right angles to the line of feed; substantially as described.

3. A folder including in combination, a main folding member and an auxiliary folding member coöperating therewith, means for yieldingly and adjustably supporting 110 the delivering end of said auxiliary folder and means for adjusting the same bodily longitudinally of the main folding member; substantially as described.

4. A sewing machine, comprising in combination stitch-forming mechanism, feeding mechanism and a folder including in combination, a main folding member and an auxiliary folding member coöperating therewith, means whereby said auxiliary folding member may be bodily adjusted relative to said main folder, and means whereby the delivery end of said auxiliary folder may be laterally adjusted relative to the main folder, said folder being located substantially 120 at right angles to the line of feed; substantially as described.

5. A sewing machine comprising feeding mechanism, and a folder including in combination, a main folding member having 125

- means for folding the edge of a strip to be folded, and an auxiliary member located within said main folder and engaging and folding said strip between its edges, and 5 means for adjusting said auxiliary member longitudinally of said main folder, said folder being located substantially at right angles to the line of feed; substantially as described.
- 10 6. A sewing machine comprising feeding mechanism, and a folder including in combination, a main folding member having means for folding the edge of a strip to be folded, and an auxiliary member located within said main folder and engaging and folding said strip between its edges, means for adjusting said auxiliary member longitudinally of said main folder, and means for adjusting the delivery end of said auxiliary member transversely of said main folder, said folder being located substantially at right angles to the line of feed; substantially as described.
- 15 7. A folder including in combination, a main folding member having means for folding the edge of a strip to be folded, and an auxiliary member located within said main folder and engaging and folding said strip between its edges, a screw stud carried by said auxiliary folding member adjacent its receiving end and projecting through a slot in the main folder, a thumb nut for securing said auxiliary member in its adjusted positions, and means for adjusting the delivering end of said auxiliary folder transversely of said main folder; substantially as described.
- 20 8. A folder including in combination, a main folding member having means for folding the edge of a strip to be folded, and an auxiliary member located within said main folder and engaging and folding said strip between its edges, a screw stud carried by said auxiliary folding member adjacent its receiving end and projecting through a slot in the main folder, a thumb nut for securing said auxiliary member in its adjusted positions, and a screw stud carried by said auxiliary member adjacent its delivering end, a thumb nut carried by said last named stud, and means co-operating with said last named thumb nut for adjusting said delivering end; substantially as described.
- 25 9. A folder including in combination, a main folding member having means for folding the edge of a strip to be folded, and an auxiliary member located within said main folder and engaging and folding said strip between its edges, a screw stud carried by said auxiliary folding member adjacent its receiving end and projecting through a slot in the main folder, a thumb nut for securing said auxiliary member in its adjusted positions, and a screw stud carried by said auxiliary member adjacent its delivering end, a thumb nut carried by said last named stud, and means co-operating with said last named thumb nut for adjusting said delivering end; substantially as described.
- 30 10. A folder including in combination, a main folding member having means for folding the edges of a strip, said main folder being cut away to expose the edges, and a tension member formed from a wire bent to provide fingers for engaging the exposed edges, means for supporting said wire, and means for placing said wire under tension; substantially as described.
- 35 11. A folder including in combination, a main folding member, an extension carried thereby, co-operating arms pivotally carried by said extension, means for securing said arms in adjusted positions, and guides carried by said arms for guiding the strip to the folder; substantially as described.
- 40 12. A folder including in combination, a main folder having means for folding the edges of a strip, said main folder being cut away to expose the edges, and a tension member formed from a wire bent to provide fingers for engaging the exposed edges, means for supporting said wire, a yoke bearing on said wire, and means engaging said yoke for placing the fingers under tension; substantially as described.
- 45 13. A folder including in combination, a main folder, having means for folding the edges of a strip, said main folder being cut away to expose the edges, and a tension member formed from a wire bent to provide fingers for engaging the exposed edges, means for supporting said wire, a yoke bearing on said wire, and means engaging said yoke for placing the fingers under tension; substantially as described.
- 50 14. The combination of a folder for folding and inverting a binding strip, said folder including a member for engaging the binding strip at the fold therein and over which member said strip is inverted, means for adjusting said member for different widths of strips, an edge guide for the body fabric independent of the folder, and means for adjusting the edge guide so as to properly position the fabric relative to the folded strip.
- 55 15. The combination with a work support and stitch-forming mechanism, of a folder having its longitudinal axis at right angles to the line of stitching, means whereby said folder may be adjusted for different widths of strips, and an edge guide for a body fabric, and means whereby said edge guide may be adjusted to properly position the body

10 fabric relative to the folded strip; substantially as described.

15 16. A main folder having means for folding a fabric and for inverting the folded strip, guiding fingers fixed to said folder for guiding the edge of the folded strip after it is inverted, and an auxiliary folder located within the main folder, and means for adjusting said auxiliary folder to accommodate strips of different widths.

20 17. A folder for bindings composed of a body tapered from its middle to its opposite ends, and having at one end thereof edge-folding means, and at its other end edge-uncurling means, the latter comprising a tapered extension of said end of the body forming a rigidly set tongue, said tongue having its end rounded, whereby the edges of the material engage the edges of the extended tongue and are uncurled thereby.

25 18. A folder for sewing machines composed of two blanks shaped and combined so as to produce a body tapered in opposite directions, said body having at one end thereof edge-folding means and at its other end edge-uncurling means, the latter means comprising a tapered rounded end of one of the blanks forming a rigidly-set tongue extension of said body whereby the edges of the material engage the edges of the tongue and are uncurled thereby.

30 19. A folder for bindings composed of a body tapered from its middle to its opposite ends, said body having at one end thereof edge-folding means and at its other end edge-uncurling means, the latter means consisting of opposed loops, formed on one side of the body, in combination with a tapered extension of said end of the body forming a rigidly-set rounded tongue coöperating with said opposed loops, whereby the edges of the material are operated upon by the loops and the extended tongue and are uncurled thereby.

35 40 20. In a binding attachment for sewing machines, a binder head comprising a guiding element for guiding the binding in a direction transverse to the line of feed of the material being bound, the delivery end of said element being formed obliquely with respect to its length, whereby the binding may be inverted, a guiding member for engaging the material at the fold therein and over which said folded material is inverted, and means for adjusting the said member for varying the capacity of the folder for different widths of binding strips.

45 50 55 60 21. In a binding attachment for sewing machines, a binder head comprising spaced U-shaped guiding walls, for guiding the binding in a direction transverse to the line of feed of the material being bound, the delivery end of said walls being formed obliquely with respect to the length of the folder, whereby the binding may be invert-

ed, a guiding member for engaging the material at the fold therein and over which said folded material is inverted, and means for adjusting said member longitudinally of the binder head for varying the capacity of the folder for different widths of binding strips.

65 70 75 80 85 22. In a binding attachment for sewing machines, a binder head comprising spaced guiding walls for guiding the binding in a direction transverse to the line of feed of the material being bound, the delivery end of said binder being formed obliquely with respect to its length, whereby the binding may be inverted, a guiding member having a U-shaped cut-away portion at its delivery end, said guiding member being so disposed as to engage the material at the fold therein, whereby said folded material may be inverted over said guiding member, and means for adjusting said member for varying the capacity of the folder for different widths of binding strips.

90 95 100 105 23. In a binding attachment for sewing machines, a binder head comprising a guiding element for guiding the binding in a direction transverse to the line of feed of the material being bound, the delivery end of said guiding element being formed obliquely with respect to its length, whereby the binding may be inverted, guiding fingers fixed to the binder head for guiding the edges of the folded strip after it is inverted, a guiding member for engaging the material at the fold therein over which said folded material is inverted, and means for adjusting said member toward and from said guiding fingers for varying the capacity of the folder for different widths of binding strips.

110 115 24. In a folding device, spaced walls for guiding the material and having the delivery end of said spaced walls arranged at an acute angle to the longitudinal axis of the spaced walls, a guiding device coöperating with the inner wall and being shaped to conform to the curvature of the inner wall with which it coöperates, said guiding device being located at the delivering end of the folding device, and means whereby said guiding device may be adjusted longitudinally of the folder for varying the capacity of the folder for different widths of strips.

120 125 130 25. The combination of a stitch forming mechanism, of a folder, means for supporting said folder with its longitudinal axis substantially at right angles to the line of stitching, said folder comprising continuous guiding walls adapted to guide a binding strip, said guiding walls at the delivery end thereof being shaped so that said strip may be inverted as it is led from the folder to the stitching mechanism, said guiding walls of the folder between the receiving and de-

livering ends thereof having means for turning the edges of the strip outwardly and backwardly upon the strip whereby when said strip is inverted said edges will be brought between the inner side faces of the binding strip, a guiding member for engaging the material at the fold therein over which said folded material is inverted, and means for adjusting said member for varying the capacity of the folder for different widths of binding strips.

26. The combination with stitch forming mechanism, of a folder, means for supporting said folder with its longitudinal axis substantially at right angles to the line of stitching, said folder comprising substantially continuous guiding walls adapted to guide a binding strip, said guiding walls at the delivery end thereof being shaped so that said strip may be inverted as it is led from the folder to the stitching mechanism, said guiding walls of the folder between the receiving and delivering ends thereof

having means for turning the edges of the strip outwardly and backwardly upon the strip, whereby when said strip is inverted said edges will be brought between the inner side faces of the binding strip, said folder between its receiving and delivering ends including means for folding the binding strip between its edges whereby said binding strip may be led into the receiving end of the folder in a substantially flat vertical position, a guiding member for engaging the material at the fold therein over which said folding material is inverted, and means for adjusting said member for varying the capacity of the folder for different widths of binding strips.

In testimony whereof I affix my signature, 40 in presence of two witnesses.

JAMES R. MOFFATT.
